UNITED STATES PATENT OFFICE.

CHARLES E. ATTWOOD, OF WOLLASTON, MASSACHUSETTS, ASSIGNOR TO POSTINDEX COMPANY, INC., OF BOSTON, MASSACHUSETTS, A CORPORATION OF MASSACHUSETTS.

FILING AND INDEXING EQUIPMENT.

Application filed December 3, 1925. Serial No. 72,947.

This invention relates to novel and improved filing and indexing equipment having a changeable filing element, which can be changed or shifted from time to time to present different areas to view.

The invention will be best understood by reference to the following description, when taken in connection with the accompanying drawings of one specific embodiment thereof, while its scope will be more particularly pointed out in the appended claims.

In the drawings:

Fig. 1 is an elevation of a filing and indexing equipment embodying the invention;

Fig. 2 is an elevation of one of the filing elements as it appears when unfolded; and

Fig. 3 is a sectional view of one of the filing elements in its folded condition on line 3-3 of Fig. 2.

Referring to the drawings, and to the embodiment of the invention which is selected for exemplification, there is shown a filing and indexing equipment comprising a series of changeable filing elements 5, which can be changed or shifted from time to time to present different areas to view. In the present example, each of these filing elements comprises an endless band of paper, weakened as by scoring along parallel lines 6. Between these lines, there are areas 7 which may be written upon for various purposes, one of which is to exhibit the changing balances of accounts. This is conveniently accomplished by variously folding the element from time to time along the several scored lines, thereby causing different areas for the writing of balances to be exposed at the inspection point. In the present example, these filing elements are disclosed in overlapping relationship in such a manner that one of writing areas of each element is presented to view at one time (see Fig. 1).

Herein, the filing elements are supported by parallel sheet-supporting bars, such as flexible wires 8, having enlarged terminals such as cylindrical trunnions 9, which are received in appropriate bearings presented by opposed channels 11, conveniently formed by a sheet-metal panel 12 having two opposite marginal portions bent to form flanges 13, which overlie the trunnions (see Fig. 1). Each endless band is conveniently attached to its supporting bar by

being looped over and around the wire (see Fig. 3). The trunnions on the wires space the latter, and predetermine the degrees of overlap of the filing elements. In the present example, this amount of overlap is substantially equal to the spacing between two adjacent scored lines 6. The dimensions of the filing elements may be made to suit the circumstances, and in particular, the dimension lengthwise of the scored lines may be such as to provide a writing area of any needed length, although in the present example, the filing elements are comparatively narrow, and the writing spaces are correspondingly short,—much shorter in fact than the length of the supporting bars.

As already intimated, one of the possible uses of the changeable filing element is to enable the balance of an account to be exhibited and readily ascertained, without exposing the entire record or account, and this is rendered conveniently possible in the present example by associating with each of the filing elements 5 a second filing element, herein comprising a folded sheet 14 presenting two leaves 15 and 16, the latter extending beyond the former (see Fig. 3), as at 17, and presenting an identification-receiving marginal surface 18 (see Figs. 1 and 2), which may be used for the writing of the name of an individual, firm, corporation or other designation of the subject matter contained in the record. These margins are arranged in overlapping relationship, so that all of the identifications are presented to view at one time.

The remaining surface of each of the filing elements 14 may be used for the keeping of a more complete record of the matter in question. For example, in the case of a bank account, the normally concealed portion of the sheet may be ruled as in Fig. 2 to present columns and horizontal divisions for the entries, the columns being appropriately designated, as for example: "Date", "Deposit", "Withdrawal", and "Balance". The deposits and withdrawals made from time to time may be indicated in the appropriate columns, and the balance ascertained and placed in its appropriate column. At the same time that the amount of the balance is written in its column, it is intended that it shall also be written on the exposed writing area of the associated

changeable element 5, as illustrated in Fig. 2. When there is another deposit or withdrawal, or interest is added, the amount of the balance will appear in its proper column on the element 14, as well as in the next space on the element 5, which is then shifted to bring the new balance to view at the exposed margin, where it may be examined without the necessity of opening the file to examine the account itself on the element 14. Thus it is evident that in the case of a so-called visible index, all of the balances are presented to view at one time, resulting in a great saving of time and clerical labor. It should be understood, of course, that the idea is useful for other purposes, such as indicating stocks of merchandise on hand, and other uses which will readily suggest themselves. It should also be apparent that in some cases, the use of the elements 14 may be dispensed with altogether.

The elements 14 are appropriately supported by the bars, as by having the latter received within their folds, and said elements may be secured to the bars as by the provision of perforations 19 (see Fig. 2), which are intersected by the line of the fold, said perforations being large enough to allow the trunnions 9 to be passed through them in threading the sheet onto the wire. The sheet 14, when folded, is thus held against displacement transversely of the wire, and in turn holds the sheet 5 against displacement, as will be evident from an inspection of Fig. 3. Thus the two sheets, together with their supporting bar, constitute in effect a filing element having relatively movable record areas, one of which can be shifted at will relatively to the other to expose different areas to view for inspection.

Having thus described one embodiment of the invention, but without limiting myself thereto, what I claim and desire by Letters Patent to secure is:

1. In a file, the combination of a panel presenting opposed channels, a series of sheet-supports comprising wires having terminals received in said channels, a series of folded sheets associated with said wires, respectively, and having overlapping, exposed, identification-receiving margins, each sheet presenting two leaves one of which extends beyond the other and presents the identification-receiving margin, and a series of sheets, each comprising an endless band, associated with said wires, respectively, each band being looped around and embracing its associated wire and being received between the leaves of its associated, folded sheet, each band being scored at intervals along lines parallel with said wires, and each band having an exposed area presented to view upon the identification margin of its associated folded sheet.

2. In a file, the combination of a series of elongated parallel, sheet-supporting bars, a support for said bars, and a series of overlapping sheets associated with said bars, respectively, and having areas exposed simultaneously, each sheet being scored along lines parallel with said bars and being variously foldable along said lines to present different areas to view from time to time. 70

3. In a file, the combination of a series of elongated parallel, sheet-supporting bars, a support for said bars, and a series of overlapping sheets associated with said bars, respectively, and having areas exposed simultaneously, each sheet constituting an endless band looped over its associated bar. 85

4. In a file, the combination of a series of elongated parallel, sheet-supporting bars, a support for said bars, and a series of overlapping sheets associated with said bars, respectively, and having areas exposed simultaneously, each sheet constituting an endless band looped over its associated bar, and being weakened along lines parallel with said bars. 90

5. In a file, the combination of two series of overlapping record-receiving sheets, one sheet of each series being associated with one sheet of the other series, and being shiftable relatively thereto transversely of the overlapped margins to expose different areas of said first sheets to view for inspection, and means to maintain the overlapped relationship of said sheets. 95

6. In a file, the combination of two series of overlapping record-receiving sheets, one sheet of each series being associated with and normally concealing a portion of one sheet of the other series, but revealing another portion, the two associated sheets being relatively movable transversely of the overlapped margins to change the area which is revealed, and means to maintain the overlapped relationship of said sheets. 100

7. In a file, the combination of two record-receiving sheets, one sheet being associated with and normally concealing a portion of the other sheet, but revealing another portion, the sheet, a portion of which is concealed, being foldable to present different areas to view. 110

8. In a file, the combination of two record-receiving sheets, one sheet being associated with and normally concealing a portion of the other sheet, but revealing another portion, the sheet, a portion of which is concealed, being weakened along parallel lines on which it may be variously folded to present different areas to view. 120

9. In a visibly indexed file, the combination of two series of overlapped record-receiving sheets, one sheet of each series being associated with and normally concealing a portion of one sheet of the other series, but revealing another portion, the sheet of which 125

- a portion is revealed having such revealed portion superimposed upon the indexing margin of the associated sheet, and means to maintain the overlapped relationship of said sheets.
10. In a file, the combination of a series of record sheets presenting exposed, overlapping, identification-receiving margins, and having normally unexposed areas presenting ruled columns for account entries, a series of balance sheets interleaved with said record sheets and having balance-receiving areas superimposed upon the corresponding identification-receiving margins, and means to maintain the overlapped relationship of said record sheets.
11. In a file, the combination of a series of overlapping, record-receiving sheets, each weakened along parallel lines on which it is foldable to present different successive areas to view at the overlapping margins, and means supporting and maintaining said sheets in overlapping relationship with one such area of each sheet exposed to view and normally concealing the remaining areas from view.
12. In a file, the combination of a series of overlapping, record-receiving sheets, each weakened along parallel lines on which it is foldable to present different successive areas to view at the overlapping margins, other overlapping sheets with which said record-receiving sheets are interleaved, and means maintaining the overlapping relationship of said sheets.
13. In a file, the combination of a series of overlapping, record-receiving sheets, each weakened along parallel lines on which it is foldable to present different successive areas to view at the overlapping margins, other overlapping sheets with which said record-receiving sheets are interleaved, a series of sheet-supporting and positioning means each associated with one of said record-receiving sheets and with one of said other sheets, and maintaining said sheets in such overlapping relationship, and a mounting for said means.
14. In a file, the combination of a series of overlapping, record-receiving sheets, each weakened along parallel lines on which it is foldable to present different successive areas to view at the overlapping margins, a series of folded, overlapping sheets each of which receives within its fold one sheet of the first-mentioned series, and means maintaining the overlapping relationship of said sheets.
15. In a file, the combination of a series of overlapping, record-receiving sheets, each weakened along parallel lines on which it is foldable to present different successive areas to view at the overlapping margins, a series of folded, overlapping sheets each of which receives within its fold one sheet of the first-mentioned series, a series of sheet supports also received within the folds of said folded sheets, and a mounting for said supports.
16. In a file, the combination of a series of sheets having overlapping margins, a series of supporting bars associated with said sheets, respectively, and maintaining their overlapped relationship, a series of signals also supported by said bars, respectively, and having portions overlying the margins of said sheets, respectively, and a mounting for said bars.
17. In a file, the combination of a series of sheets having overlapping margins, means supporting said sheets and predetermining the amount of overlap of said margins, and a series of signals associated with said sheets, respectively, and supported by said means independently of said sheets.
18. In a file the combination of a series of sheets having overlapping margins, a series of supporting bars associated with said sheets, respectively, and maintaining their overlapped relationship, a series of signals also supported by said bars, respectively, and having portions overlying the margins of said sheets, respectively, and mounted to move lengthwise of said bars and of said margins, and a mounting for said bars.
19. In a file, the combination of a series of sheets having overlapping margins, means supporting said sheets and predetermining the amount of overlap of said margins, and a series of signals associated with said sheets, respectively, and supported by said means independently of said sheets and mounted to move lengthwise of said margins.
20. In a file, the combination of a series of sheets having overlapping margins, a series of supporting bars associated with said sheets, respectively, a series of signals also supported by said bars, respectively, and a mounting for said bars.
21. In a file, the combination of a series of sheets having overlapping margins, a series of supporting bars associated with said sheets, respectively, a series of signals having portions disposed about and attached to said bars, respectively, and a mounting for said bars.
22. In a file, the combination of a series of sheets having overlapping margins, a series of supporting bars associated with said sheets, respectively, a series of signals also supported by said bars, respectively, and mounted to slide lengthwise of said bars, and a mounting for said bars.
23. In a file, the combination of a series of folded sheets having overlapping margins, a series of supporting bars for said sheets, respectively, a series of signals associated with said sheets, respectively, each signal being received in the fold of its associated sheet, and a mounting for said bars.

24. In a file, the combination of a series wise of the margin of its associated sheet, of folded sheets having overlapping margins, a series of supporting bars for said sheets, respectively, a series of signals associated with said sheets, respectively, each signal being received in the fold of its associated sheet and mounted on its associated bar, and a mounting for said bars.
25. In a file, the combination of a series 10 of folded sheets having overlapping margins, a series of supporting bars for said sheets, respectively, a series of signals associated with said sheets, respectively, each signal being received in the fold of its associated sheet and mounted to move length-
26. In a file, the combination of a series of folded sheets having overlapping margins, a series of supporting bars for said 20 sheets, respectively, a series of signals associated with said sheets, respectively, each signal being received in the fold of its associated sheet and mounted on and movable lengthwise of its associated bar, and a 25 mounting for said bars.

In testimony whereof, I have signed my name to this specification.

CHARLES E. ATTWOOD.
